UNITED STATES PATENT OFFICE.

HERMAN C. WELTER, OF ROCHESTER, NEW YORK, ASSIGNOR TO HALL-WELTER CO.,
INC., OF ROCHESTER, NEW YORK,
PRINTING MECHANISM AND SUBINKING MEANS THEREFOR.

1,174,642.

Specification of Letters Patent. Patented Mar. 7, 1916.

Application filed December 22, 1915. Serial No. 68,235.

To all whom it may concern:

Be it known that I, HERMAN C. WELTER, a citizen of the United States, residing at Rochester, in the county of Monroe and State of New York, have invented a new and Improved Printing Mechanism and Subinking Means Therefor, of which the following is a specification:

My invention relates to printing mechanism and especially to that class embodying machines known as check writers and check protectors. In machines of this character, there have been provided various ways of having the coöperating printing members not only print certain selected characters on a check, or other negotiable instrument, but in so doing to break the paper throughout the printed surface in a manner that ink from the type will be absorbed by the disrupted fibers, the purpose of such mutilation being also to prevent erasure of the printed characters which cannot be effected without tearing the paper.

Heretofore, the construction and operation of the printing mechanism has been such that ink is applied from the type to the face only of the instrument being printed; and it is the object of this invention to provide a platen or die member adapted to cooperate with the type whereby, in forming characters by an embossing or punching operation, ink will be applied to such characters on both sides of the paper, and at the same time there will be a disruption of the fibers.

Another object of the invention is to supply ink to the sub-inking means from the type characters when coming in contact therewith during the printing operation; and a still further object is, preferably, to make the type characters the cutting means and to so relatively conform the die member thereto that the action in disruption of the fibers is more of a tear than a clean cut.

In the accomplishment of my invention, I make use of a die member the face of which comprises a plurality of parallel extending wires formed in either of two ways, as will be explained, and spaced equal distances apart to form openings therebetween through which projecting ridges on the coöperating type characters are adapted to engage. These type characters are carried on a support which is movable to bring a selected line of type opposite the die, and the

two members are movable relatively toward and into engagement with each other for the printing operation.

Beneath the wires and in engagement therewith is an ink pad against which the under side of the paper is forced by projecting portions of the type characters, thus causing the paper to be inked on the under and embossed side while the impressions made in the face side of the paper by the type characters are inked therefrom. The type is inked by any suitable means which, when the support therefor comprises a type cylinder, is usually one or more ink rollers removably held in yielding contact therewith. The pad is suitably inked before being inserted to place but cannot become dry, as sufficient ink to keep it in proper condition is supplied thereto from the edges of the type characters which contact therewith when cutting through the paper of the instrument being printed. The die forming wires, though being under tension, have a certain amount of resiliency permitting them to properly center in their respective grooves of the engaging type characters and whereby they tend to hold the depressed portions of paper being printed in contact with the side faces of the type character ridges thus insuring a more perfect printing contact.

The accompanying drawings illustrating my invention are as follows:

Figure 1 is a plan view of the sub-inking die member; Fig. 2, a longitudinal sectional view thereof taken along the line $x-y$ of Fig. 1; Fig. 3, a transverse sectional view taken along the line x^1-y^1 of Fig. 1; Fig. 4, a plan view showing a modified construction of the die; Fig. 5, a longitudinal sectional view taken along the line x^2-y^2 of Fig. 4; Fig. 6, an end view of the die shown in Figs. 4 and 5 as seen from the right of such figures; Fig. 7, a side elevation of a check writing machine in which the invention is adapted to be used; Fig. 8, a fragmentary portion of the type support showing in plan view part of a line of type; Fig. 9, a longitudinal sectional view of a portion of the die member shown in Figs. 1, 2 and 3 with type characters in operative engagement therewith; while Figs. 10 and 11 illustrate the appearance of the face and reverse sides, respectively, of a check when printed. All of the figures with the exception of 7 are drawn to a greatly enlarged scale.

Similar reference characters refer to similar parts throughout the several views.

Referring first to Fig. 7: At 1 is seen the base and at 2 the head of a check writing machine of the character for which the invention is more especially intended, the front portion of the head being spaced apart from the base to receive a check 34 therebetween, which is supported on the 10 plate 3. In this machine the type bars 4 extend longitudinally of and are carried on the periphery of a cylinder 5 rotatably supported in bearings 6 slidable in vertically extending guideways 7 in the side walls of 15 the head member 2. This cylinder may be turned to bring any predetermined line of the type directly above the platen or die 8 supported in the member 9, forming an integral part of the base 1, and it is raised and 20 lowered by the toggle levers 10 and 11 on actuation of the operating lever 12. At 13 is seen the usual ink roller mounted in suitable supporting arms 14 and held in yielding engagement with the type wheel 5 for 25 supplying ink to the characters on the several type bars.

The form of die member shown in Figs. 1, 2 and 3, comprises a rectangular block or bar 15 having a centrally disposed longitudinally extending slot 16 of a width equal to that of the type characters. Across this slot and forming the face of the die are a plurality of equally spaced parallel wires 17 seated in grooves formed therefor in the top 30 of the bar and secured to place by having their ends turned down against the side faces of such supporting bar and soldered thereto, the solder being indicated at 18. The depth of the slot 16 is sufficient to permit 35 an ink pad 19 being placed therein which engages the bottom of the wires. The sub-inking die thus formed is seated in a slot 20 therefor in the supporting member 9 forming an integral part of the base 1 of the machine and indicated at 8 in Fig. 7. Any preferred means for adjusting the die 8 in the slot 20 of the supporting member to secure a proper registration of the die wires with the type characters may be provided as, for instance, the screw 21 threaded into a hole 22 in the die bar 15 and in which the bar is the movable member.

Refer now to Figs. 4, 5 and 6: At 23 is seen a block or bar similar to the one 15 above described. This bar has a longitudinally extending slot 24 adapted to receive therein a coiled spring 25 in which is contained an ink pad 35, such spring when wound being formed preferably, on a rectangular bar as it is necessary that the top portions at least of the several convolutions, which form the face of the die, will be formed on a flat surface. At each end of the slot 24 is a block, one of which 26 is held 60 stationary and the other 27 is a movable

member, and these blocks are provided with outwardly extending side flanges 28 engaging in slots 29 therefor in the bar 23 to prevent displacement. One end of the spring 25 extends under and is formed up against the outer end of the block 26 while the other end thereof extends under and is similarly formed against the outer end of the movable block 27. This form of die is also adapted to be seated in the above referred to slot 20 70 in the supporting member 9 forming a part of the base 1 of the machine, see Fig. 7, and is adjustable in the manner described for the block 15. A screw 30, having a shoulder 31 therein engaging in a transverse slot 32 75 formed in an extended portion of the bar 23, is threaded into the block 27, such block being caused to move longitudinally in the slot 24 on turning the screw; and it will thus be seen that a movement of the block causes 80 the spring to be placed under a greater or less tension whereby the opening or closing of the several coils adjusts them to the 85 grooves formed in the type characters which coöperate therewith in the printing operation. 90

The impressing members are type characters made, preferably, of hard metal with the face thereof serrated, as will be hereafter described, or of a comparatively soft composition into which impressions of the wires forming the top of the die member will be made by contact therewith under sufficient pressure, the function of the type being to both print on the face of the paper and to 100 force portions thereof through the openings between the die wires into contact with the ink pad thereunder, the result being an inking of the impressed character on both sides of the paper. 105

The type characters 33 shown in the drawings are formed on bars 4 extending longitudinally of and secured on the periphery of the cylinder or wheel 5. Parallel grooves are formed in the type of a depth less than the thickness of the bars above the surface of the wheel and so disposed as to register with the wires forming the top of the die. It will thus be seen that the type characters will have ridges alternating with the grooves and it is preferable that these ridges be formed with sharp cutting edges. When coming in contact with the sides of the type character ridges, the resiliency of the die wires will cause them to become properly 110 centered in their respective grooves. 115

When employing my invention the coöperation of the type and sub-inking die member will be such as to impress the characters into the paper in a manner to break the fibers, and, also, to ink such characters on both the face and reverse sides of the paper, as shown in Figs. 10 and 11, respectively. As before stated, the sub-inking pad will be suitably inked before inserted to place 120 125 130

but will not at any time become dry as sufficient ink will be applied thereto from the ridges of the type characters when cutting or breaking through the paper during the printing operation.

It is believed that, from the foregoing description, the construction, purpose and manner of using the invention are sufficiently clear to call for no further explanation.

What I claim is:

1. In a printing machine of the character described, the combination with type characters of a die comprising a plurality of 15 equally spaced parallel extending wires and a support therefor, and an ink pad in contact with said wires on the side thereof opposite that engaged by said type characters.

2. In a printing machine of the character 20 described, the combination with type characters of a die comprising a coiled spring and a support for the spring.

3. In a printing machine of the character described, the combination with type characters 25 of a die comprising a coiled spring and a support therefor, and an ink pad within said spring and in contact with the portions thereof engaged by said die type characters.

4. In a printing machine of the character 30 described, the combination with type characters of a die member comprising a channeled bar and a coiled spring within the channel, and a support for the bar.

5. In a printing machine of the character 35 described, the combination with type characters of a die member comprising a channeled bar and a coiled spring within the channel, a support for said bar, and an ink pad within said spring and in contact with the portions thereof engaged by said type characters.

6. In a printing machine of the character 40 described, the combination with type characters of a die member comprising a channeled bar and a coiled spring within the channel, a support for said bar, an ink pad within said spring and in contact with the portions thereof engaged by said type characters, and means for adjusting the tension 45 of said spring.

7. In a printing machine of the character 50 described, the combination with type char-

acters of a die member comprising a channeled bar and a coiled spring within the channel, a support for said bar, a fixed member to which one end of the spring is secured, a movable member to which the other end of the spring is secured, and means for moving said last named member for adjusting the tension on said spring.

8. In a printing machine of the character described, the combination with type characters of a die member comprising a channeled bar having side walls and slots formed in such walls, a support for the bar, a coiled 65 spring within said channel, two blocks to which the opposite ends of said spring are secured, one of the blocks being a fixed and the other a movable member, flanges on said blocks engaging in said slots, and means for 70 adjusting the movable block longitudinally in said channel for the purpose specified.

9. In a printing machine of the character described, the combination with type characters grooved to form a plurality of parallel 75 extending ridges, of a die comprising a plurality of equally spaced parallel extending wires, an adjustable support for the wires, means for inking said type characters, an ink pad on the side of said wires opposite 80 that engaged by said type characters, and means for moving said type and said die relatively toward each other to impress a check held between them, the coöperating action of the engaging members being to print on 85 both sides of the impressed characters and to break the fibers of the paper throughout the printed surface.

10. In a printing machine of the character described, the combination with type 90 characters grooved to form a plurality of parallel extending ridges, of a die comprising a coiled spring, an adjustably supported container for said spring having an open 95 face, means for inking said type characters, an ink pad within said spring, and means for moving said type and said die relatively toward each other to impress a check held between them, the coöperating action of the engaging members being to print on both 100 sides of the impressed characters and to break the fibers of the paper throughout the printed surface.

HERMAN C. WELTER.
